CLAIM

We claim the ornamental design for a paper caddy, as shown and described.

DESCRIPTION

FIG. 1 is an exploded perspective view of a paper caddy showing our new design;

FIG. 2 is a front view, in perspective, of parts assembled together.

FIG. 3 is a top view.

FIG. 4 is a front elevational view.

FIG. 5 is a right side view.

FIG. 6 is a left side view.

FIG. 7 is a rear elevational view showing the wall mounting holes.

FIG. 8 is a view of the bottom.

FIG. 9 is a top view showing the handle.

FIG. 10 is a front elevational view.

FIG. 11 is a right side view.

FIG. 12 is a left side view.

FIG. 13 is a rear elevational view; and,

FIG. 14 is a view of the bottom.
